GUARD FINGER AND LEDGER PLATE FOR MOWING MACHINES

Filed May 19, 1930

FIG. 4.

Inventor

J. B. Jenson.

By Robert Cobb, Attorneys

UNITED STATES PATENT OFFICE

JAMES B. JENSON, OF SALT LAKE CITY, UTAH

GUARD FINGER AND LEDGER PLATE FOR MOWING MACHINES

Application filed May 19, 1930. Serial No. 453,566.

This invention comprises novel improvements in guard finger and a ledge plate means adapted to be used as parts of the cutting apparatus of a mowing-machine, or harvester.

The mowing-machine comprises, as usual, the necessary instrumentalities to operate the cutting knife or sickle bar with its customary means for lifting and shifting the cutting apparatus. These details of the mowing-machine are omitted from the drawing, as they form no part of this invention other than they are used in combination with the guard finger and the ledger plate.

For the guard fingers such as now used, the ledger plate is either riveted to or fastened with screws to the guard finger. The known object of the ledger plate is to provide a cutting edge to meet the cutting edge of the knife or sickle bar mounted on the cutting apparatus, and reciprocating in the guard fingers through the instrumentalities for the actuating means.

It is well known that the ledger plates become dull and incapacitated through use, and also broken or nicked by coming into contact with gravel and rocks encountered in the movement of the mowing-machine over the surface being mowed. The ledger plates under the above conditions must be removed and replaced by new ones, if the mowing-machine is to perform its functions effectually.

To replace the ledger plates now commonly used is an irksome task, due to the rivets or screws, because rivets must be chopped off and driven out, and screws become rusted in the structure, and sometimes the heads are broken off in endeavoring to remove them.

The object of this invention is to overcome this difficulty, and to improve the mounting and removal of the ledger plates. In the practice of my invention, the ledger plates may be removed or mounted in a very short interval of time, and with very ordinary and simple tools, such as a punch, a chisel or flat elongated piece of metal, or other suitable tool.

This invention is fully disclosed in the following specification, of which the accom-

panying drawing forms a part, in which the separate parts of my improvements are designated by suitable reference characters in each of the views.

Figure 1 is a top view of a guard finger 55 with the ledger plate mounted therein.

Figure 2 is a longitudinal sectional view taken about line 2—2 in Figure 1, showing the means for connecting the ledger plate to the guard finger.

Figure 3 is a sectional fragmentary view of a guard finger and the ledger plate, showing the interposition of a tool therein and thereunder, with a hammer adjacent one of the tools, to illustrate the simple method of mounting or removing the ledger plate.

Figure 4 is a cross sectional view of the guard finger and ledger plate taken on line 4—4 in Figure 1 showing the relation of the ledger plate to the guard finger.

In the drawing forming a part of this specification I have shown the guard finger A, in which the ledger plate B is removably mounted therein. The guard finger is provided with an aperture 1, adapted to receive 75 a rivet or other suitable member for the purpose of securing the guard finger in fixed relation to its associate part or parts of the mowing-machine. Adjacent the pointed end of the guard finger there is provided a pocket 80 or receiving socket 2, the lower wall or floor 3 of which, is provided with a curvature or contour 4 leading upwardly in the guard finger A. The upper integral wall 5 of the socket extends from before backward, and 85 is so positioned that it forms a transverse slot 6 with the ledger plate B when mounted in the guard finger.

This transverse slot is provided to receive the sickle or knife that may be reciprocated 90 therein. Adjacent the entrance of the pocket or receiving socket there is placed a downwardly extending and transverse rib 7, this rib is adapted to form a fulcrum or support against which the ledger plate rests when mounted in the guard finger and tending to force the rear end of the plate downwardly.

The upper wall 5 has also a semi-circular or other suitable shaped notch 8, adapted to permit the mounting of a tool used in mount-

ing or removing the ledger plate. The guard finger is provided with laterally extending arms 9 and 9', these arms provide a bearing surface for the sickle or knife. A notch or depression 10 is provided intermediate the arms, and of a depth equal substantially to the thickness of the ledger plate. A recess or depression 11 of a suitable configuration is provided in the guard finger for the reception on the rear extremity of the ledger plate. The wall 11' of the recess 11 is provided with an inclined face adapted to receive the complementary bevelled face formed on the rear end of the ledger plate. The 15 guard finger is also provided with a series of depressions 12, 13 and 14 to reduce the weight of the guard finger.

The ledger plate B is provided at one end with a reduced integrally formed portion 15, 20 forming with the ledger plate shoulders 16 and 16'. The reduced portion is mounted in the socket 2, and the socket is provided to prevent lateral displacement of the ledger plate at this extremity. The other extremity or 25 end 17 is suitably formed, and is mounted in the recess or depression formed in the guard finger provided for its reception. Lateral displacement is prohibited at this end by the squared shoulders, flanges, or ribs, 24 and 24' 30 that form a part of the perimeter that bounds the socket or depression 11 formed for the ledger plate reception. An aperture 18 is provided in the ledger plate for the reception of a suitable tool 19, to be mounted therein, 35 for the removing or mounting the ledger plate B. 20 indicates a hammer in proximity to the tool 19, depicting its use in conjunction with the removing or mounting tool. 21 indicates a tool and represents vividly its position 40 in removing the ledger plate, it being used as a lever to break the interlocking connection between the ledger plate and the guard finger. The ledger plate is slightly tapered as at 23, so that it will conform to 45 the contour of the socket wall or floor.

In practice of my invention, if it is desired to remove a ledger plate, a tool is inserted in the depression 10 and pushed under the plate B, and forced downward in the 50 direction of the arrow shown in Figure 3, this movement forces the plate up and over the angled or bevelled end of the socket 11. The tool is next placed in the aperture in the ledger plate, and the tool is struck, thus releasing the plate from the socket 2 in the 55 guard finger.

To mount the ledger plate, which is of 60 spring metal, the plate is driven into the socket 2, and because of the special construction of the socket, and the end portion of the ledger plate, the end is caused to follow the curvature or contour of the bottom wall of the socket 2. This causes the other extremity to be sprung downwardly or take a downward 65 position, when the plate has reached

the limit of its movement in the socket 2, the other end or extremity is then lifted up and then forced down and into place in the socket prepared therefor, the bevelled or angled edge of the ledger plate engages or springs 70 against the complementary face formed on the socket wall, adapted to interlock the ledger plate in the socket.

It will be apparent from the structure shown that the ledger plate is securely held 75 in place by the resiliency inherently within itself, it being made of a spring steel plate.

It will be further noted that the top of the ledger plate is flush with the top of the arms 9 and 9'.

In accordance with the patent statutes I have set forth in a specific manner required thereby one complete embodiment of my invention, but it is to be understood that this is only for illustrative purposes and that 85 the invention is capable of assuming other forms than that illustrated, and that the claims hereto annexed are not to be limited to the specific devices illustrated, except as is specifically recited therein.

Having thus described my invention what I claim as new and desire to secure by Letters Patent of the United States, is—

1. In combination, a guard finger provided with a socket, a resilient ledger plate for the guard finger and adapted to be inserted in the socket, the ledger plate having a configuration corresponding to that of the socket and snugly fitting therein, and means for interlocking the ledger plate in the guard finger, the socket being formed to maintain the interlocking action through cooperation with the inherent resiliency of the plate.

2. In combination a guard finger, provided with a socket having an upwardly curved 105 bottom, a resilient ledger plate fitting into the socket, an inwardly extending rib on the top wall of the socket, the rib being adapted to form a fulcrum adjacent the entrance of said socket and exerting a downwardly direct- 110 ed force on the rear of the ledger plate, the said ledger plate having its end fitted into the socket shaped to conform to the bottom thereof, the ledger plate also cooperating with the said fulcrum rib when mounted in the socket, 115 and means for interlocking the ledger plate in the guard finger.

3. In combination a guard finger provided with a forward socket having an upwardly directed bottom, a resilient ledger plate fitting 120 into the socket, a transverse rib integral with the top of the socket and bearing against the ledger plate, the rib being positioned adjacent the socket entrance, the said finger being provided with a recess downwardly thereof 125 to receive the rear extremity of the ledger plate, the ledger plate having a reduced and tapered forward end, shaped to conform to the upwardly directed bottom of the socket, the said ledger plate bearing against the 130

transverse rib, the end of the ledger plate being positioned in the said rear recess, and means for interlocking the ledger plate in the recess.

5 4. In combination a guard finger, a ledger plate therefor, the guard finger being provided with a socket having an upwardly curved bottom, a downwardly extending rib formed in the top of the socket and adja-

10 cent the entrance thereof, a ledger plate having a reduced and tapered end mounted in the said socket and bearing against the rib and bottom thereof, the finger having a re- cess rearwardly thereof having a bevelled

15 wall, and partial perimetrical vertical shoulders, the ledger plate having its rear end bevelled to register with the bevelled wall of the recess and interlocked therewith through the instrumentalities of the angled wall and par- 20 tial perimetrical shoulders, and an opening in the ledger plate for the reception of a tool to break the interlock.

5. In combination a guard finger, a ledger plate therefor, the guard finger being pro- 25 vided with a socket having a depending rib adjacent the entrance thereof, the ledger plate having a reduced end portion mounted in the socket and bearing against the rib, a second socket remote from the first socket,

30 the said socket being bounded by partial perimetrical squared shoulders, and having a wall other than vertical, the said wall being provided with a depression intermediate its length adapted to provide an opening 35 whereby a tool may be introduced under the ledger plate, the ledger plate being mounted in the socket and provided with an angled face and interlocking with the wall other than vertical, and being laterally limited by

40 perimetrical squared shoulders, the ledger plate being interlocked in the socket by pressure exerted by the rib upon the plate and by the inherent resiliency of the plate.

6. As a new article of manufacture, a guard 45 finger for use with a mowing-machine, the guard finger being provided with a socket having an upwardly curved bottom, a fulcrum rib adjacent the entrance of the socket depending from the top wall thereof, a sec- 50 ond socket formed remote therefrom and having a rear wall at an angle, and bounded by partial perimetrical vertical shoulders, arms extending therebeyond, and a portion having an aperture therein whereby the same 55 may be secured to the mowing-machine.

7. In combination a guard finger, a resili- 60 ent ledger plate therefor, the guard finger provided with a socket the socket having a rib adjacent the entrance thereof, a top wall 65 extending backward from the socket, and provided with a notch in the end thereof, the ledger plate having a reduced and tapered end, the end mounted in the socket, and the ledger plate cooperating with the rib and socket, the guard finger being provided with

a second socket remote from the first socket, the said second socket having an angled wall and oppositely disposed vertical shoulders, the angled wall having a depression intermediate its length adapted to provide a de- 70 pression whereby a tool may be introduced under the ledger plate, the ledger plate being resiliently secured in the socket and interlocking therewith through a complemental end on the ledger plate and the shoulders, 75 cavities in the guard finger adapted to lighten the device, and an aperture in the guard finger adapted to receive a securing device.

8. In combination, a guard finger, provided with a socket having a portion of contoured configuration in the forward end of the guard finger, the finger being also provided with a second socket remote from the first socket, a ledger plate comprising a body of resilient 80 metal having a reduced end portion mounted in the contoured socket and deflected thereby, the other end of the ledger plate formed to fit within the remote socket, and held when mounted therein by the resiliency of the 85 ledger plate.

9. In combination, a guard finger pro- 90 vided with a socket in the forward end of the guard finger and having a rib formed at the entrance thereof, a ledger plate comprising a 95 body of resilient metal having a reduced end portion mounted in the socket, the finger being also provided with a second socket remote from the first socket, the other end of the ledger plate formed to fit within the remote socket, the ledger plate being opera- 100 tively related to the rib and deflected thereby, the ledger plate being held when mounted in the remote socket by the resiliency of the 105 ledger plate.

10. In combination, a mowing-machine 110 guard finger provided with a ledger plate engaging socket, and a resilient ledger plate engaged at one end with said socket and placed under tension thereby, the finger hav- 115 ing means to interlock with the other end of the plate and maintained so interlocked by the spring tension under which the plate is placed without other fastening means.

In testimony whereof I affix my signature. 115
JAMES B. JENSON.
